UNITED STATES PATENT OFFICE

ALVIN C. GODDARD, OF FOREST HILLS, NEW YORK

METAL DOOR

Application filed April 11, 1929. Serial No. 354,227.

This invention has reference to metallic doors and similar structures employing panels, and has particular reference to the construction of the molding and the manner of assembling the panels, molding, stiles and rails.

My invention comprises a one piece molding which embraces both sides of the panels, the base of which has an interlocking engagement with the stiles and rails.

Among the objects of my invention is the provision of a strong, rigid structure, easy and simple to manufacture and assemble, and one which will present a pleasing appearance to the eye.

The invention will be hereinafter illustrated and particularly described in connection with two embodiments of the invention, both relating to metallic doors. In one embodiment, the invention is illustrated and described in connection with a metal door having a wooden filler, and in the other embodiment it is shown and described in connection with a hollow metal door.

In the accompanying drawings:

Fig. 1 represents an elevation of a corner of a door constructed in accordance with my invention;

Fig. 2 is a section on the line 2—2 of Figure 1;

Fig. 3 is a section similar to Fig. 2, showing the application of the invention to a hollow metal door, and

Figs. 4 and 5 illustrate the manner in which the molding is formed.

In the form shown the stile 1 and rail 2 are sheet metal members which are bent to a U-shape in cross section. At their corners these members are joined in overlapping relation, in the well known manner, and in this instance the stile is shown as overlapping the rail. The overlapping portions are secured together by spot welding. The edges of the U-shaped stiles and rails are inwardly 40 reversely bent, extend parallel to the sides

thereof for a short distance and are then bent inwardly at a right angle to form ledges or flanges 3 which support the double molding 4.

In the form shown in Figures 1 and 2 the 50 stiles and rails are provided with a wooden filler member 5 which lends rigidity to the structure and at the same time constitutes a support for the ledges 3. The filler member has a channel cut in the edge thereof intermediate the ends of the flanges 3, the purpose of which will hereinafter appear.

The double molding 4 is constructed from a single piece of sheet metal. A strip of sheet metal is rolled or bent into the desired 60 ornamental form, each half of the strip on either side of a longitudinal central line taking the shape of the molding as it will appear on the finished door on either side of the panel. As shown in Figures 4 and 5, the 65 metal strip is bent to form the molding members 6 and 7 on either side of a central piece 8. The strip so formed is cut to the desired length and the ornamental side members 6 and 7 are cut at an angle of 45° to the center 70 piece 8, as shown in Fig. 5, so as to provide a miter joint. The center piece 8 is then bent to form a channel as shown dotted in Figure 4, the ornamented side molding members 6 and 7 on either side of the center piece 8 75 being brought into converging relation thereby. Between these integral parallel moldings the panel 9 is received and extends down into and is embraced by the channel formed in the center piece or base 8 which in turn is 80 received within the inturned edges of the U-shape stile or rail; the channel in the base 8 being received in the channel formed in the edge of the filler 5 intermediate the flanges 3.

In the construction shown in Figure 3, which is that used in the hollow metal door, the stiles, rails and molding are constructed as hereinbefore described. In this construction, the ledges 3, on which the molding car- 90

rying the panel, rests, is supported by a reinforcing strut 10. The strut 10, which is secured to the inwardly extending flanges 3 by spot welding or the like, is bent at a right angle at the side edges thereof to form flanges 11 which are received between the reversely bent portion of the edges of the U-shape stile or rail. At the center, the strut is bent to form a channel to accommodate the channel formed in the base 8 of the molding.

From the above description, it will be apparent that the molding may be assembled about the panel and the panel and molding assembled in the door as a single piece.

It is obvious that the invention may be applied to structures other than metal doors. It might, for instance, be used to good advantage in connection with movable partitions and like structures employing panels of wood, metal, glass, or the like. It is understood, therefore, that I wish to be limited only by the scope of the appended claims as applied to any analogous structure.

I claim:

1. As an article of manufacture, a double molding for constructions employing stiles, rails and panels comprising a base having seating portions adapted to abut against stile and rail members and a channel portion between said seating portions adapted to receive the edge of a panel, and side members extending from the base in a direction opposite to the channel portion of the base and constituting the visible portion of the molding.

2. As an article of manufacture, a double molding for constructions employing stiles, rails and panels comprising a base having seating portions adapted to abut against stile and rail members and a portion extending therefrom between said seating portions and forming a channel which is adapted to receive the edge of a panel, and side members constituting the visible portion of the molding extending from the base in a direction opposite to the portion of the base forming the channel.

3. As an article of manufacture, a double molding for constructions employing stiles, rails and panels comprising a base having seating portions adapted to abut against stile and rail members and a portion extending therefrom between said seating portions and forming a channel which is adapted to receive the edge of a panel, and converging side members constituting the visible portion of the molding extending from the base in a direction opposite to the portion of the base forming the channel.

4. As an article of manufacture, a double molding constructed from a single piece of sheet metal for constructions employing stiles, rails and panels, comprising a base having seating portions adapted to abut against stile and rail members and a portion extending therefrom between said seating portions and forming a channel which is adapted to

receive the edge of a panel, and ornated converging side members constituting the visible portion of the molding extending from the base in a direction opposite to the portion of the base forming the channel.

5. In a metal door or the like, sheet metal U-shape stile and rail members having inwardly extending opposed lateral, longitudinal flanges adjacent the inner edges thereof, a double molding comprising a base having seating portions abutting against the flanges on said stile and rail members and a channel portion between said seating portions, and side members constituting the visible portion of the molding extending from the base, and a panel extending into the molding between the sides thereof, the edge of the panel being received in the channel portion of the base.

6. In a metal door or the like, sheet metal U-shape stile and rail members having inwardly extending opposed, lateral, longitudinal flanges adjacent the inner edge thereof, a double molding comprising a base having seating portions abutting against the said flanges on the stile and rail members and a portion extending into the stile and rail members between said flanges and forming a channel, and opposed side members constituting the visible portion of the molding extending from the base in a direction opposite to the channel portion of the base, and a panel extending into the molding between the sides thereof, the edge of the panel being received in the channel formed by the portion of the base of the molding extending into the stile and rail members.

7. In a metal door or the like, sheet metal U-shape stile and rail members constructed from a single piece of sheet metal reversely bent at the edges thereof and bent inwardly at right angles adjacent the edges thereof to form opposed, inwardly extending, lateral, longitudinal flanges, a double molding constructed from a single piece of sheet metal comprising a base having seating portions abutting against the flanges on said stile and rail members and a portion extending into the stile and rail members between said seating portions and forming a channel, and opposed ornated, converging side members constituting the visible portion of the molding extending from the base in a direction opposite to the channel portion of the base, and a panel extending into the molding between the sides thereof, the edge of the panel being received in the channel formed by the portion of the base of the molding extending into the stile and rail members.

8. As an article of manufacture, a double molding comprising a base having seating portions adapted to abut against stile and rail members and a channel therein adapted to receive the edge of a panel, and converging sides extending from the base.

9. As an article of manufacture, a double

molding constructed from a single piece of sheet metal comprising a base having seating portions adapted to abut against stile and rail members and a channel formed therein adapted to receive the edge of a panel, and integral converging sides extending from the base.

In witness whereof, I hereunto subscribe my signature.

10 ALVIN C. GODDARD.
